FOLDED BLANK BOX

David H. Shapiro, Montreal, Quebec, Canada

Application July 28, 1951, Serial No. 239,049

3 Claims. (Cl. 229—31)

1

This invention relates to improvements in folded blank boxes formed by bending a single blank of sheet material along predetermined fold lines to provide a box comprising bottom, side and end walls and foldable corner portions integrally connecting the side and end walls at each end of the box. The invention is particularly concerned with boxes of this type in which each end wall comprises inner and outer end wall sections and in which the foldable corner sections are connected between the side walls and the outer end wall sections and are confined, in folded condition, between the inner and outer sections of the end walls during erection of the blank in box formation.

An important object of the invention is to provide a box of the type referred to wherein parts of the blank which require to be folded over and permanently secured to other parts of the blank to provide for the desired releasable interlocking of the side and end walls of the box through the agency of the foldable corner portions are permanently secured in their folded position solely by adhesive, thereby eliminating the use of metal stapling or metal stitching and providing a box which can readily be formed on available automatic box blank folding and gluing machines and which can be set up and collapsed with greater ease and less damage to the material of the box than similar boxes heretofore available.

Another object is to provide a box of the character described in which improved means are provided for securing the inner end wall sections of the box in place in the set-up condition of the box.

Another object of the invention is to provide a box of the character described in which the inner end wall sections are adhesively secured to the outer end wall sections and are creased in a novel manner to permit the necessary relative movement between the hingedly connected parts of the foldable corner portions during both the setting up and collapse of the box.

Other objects, characteristic features and advantages of the invention will be apparent from the following detailed description of the accompanying drawings, in which:

Fig. 1 is a plan view of the blank from which my improved box is formed.

Fig. 2 is a fragmentary perspective view showing the manner in which parts of the blank are machine-folded and glued to other parts of the blank to facilitate subsequent setting up and collapse of the box.

Figs. 3 to 5 inclusive are fragmentary perspec-

2

tive views illustrating the successive steps involved in erecting the blank into box formation.

Figs. 6 and 7 are fragmentary perspective views illustrating slight modifications of the invention.

5 Referring to Figure 1, 5 designates a blank provided with score lines defining a bottom wall section 6, side wall sections 7, outer and inner end wall sections 9 and 10 and corner portions 11. Each corner portion 11 comprises a part 12 10 joined to a side wall section 7 along line 13 and another part 14 joined to the adjacent end wall section 9 along score line 15. The parts 12 and 14 of each corner portion are partially separated along the diagonal slit 16 and are hinged together along the diagonal score line 17. The slit 16 and score line 17 of each corner portion converge from opposite ends of score line 13 and meet at their inner ends. Each inner end wall section 10 15 is divided, by diagonal score or crease lines 18, into a central portion 19 and terminal portions 20, the latter being hingedly connected to the central portion 19 along the score lines 18. These portions 19 and 20 of each inner end wall section 10 20 are provided with separate flap extensions 21 joined thereto along score lines 22. The manner in which the blank is formed into a box is illustrated in Figures 2 to 5 inclusive.

The side wall sections 7 are folded inwardly along the score lines 24 to overlie the bottom wall 6, as shown in Fig. 2. At the same time, corner sections 11 are folded inwardly along the score lines 15 to overlie the outer end walls 9, as also shown in Figure 2. During this operation, the parts 14 of the corner portions 11 are 35 firmly united to the underlying end wall sections 9 by means of the paste or adhesive indicated at 25 in Fig. 1. The inner end wall sections 10 are now folded inwardly along the score lines 26 to overlie both the outer end wall sections 9 and the infolded corner portions 11, as also shown to 40 advantage in Figure 2. The central portions 19 of the infolded end wall sections 10 are firmly united to the portions 17 of the infolded corner sections 11 by means of adhesive indicated at 27.

45 If desired, the central portions 19 of the infolded inner end wall sections 10 may also be glued directly to the central portions of the end wall sections 9.

The foregoing operations complete the folding and the pasting of the blank into box formation but leave the box in the flat or collapsed condition shown in Fig. 4. In setting up the box the end portions formed by the end wall sections 9 and 10 are bent upwardly along the crease lines 29, as shown in Figure 3. During

this operation the parts 12 and 14 of the corner portions 11 fold together along the hinge connection 17 so that the part 12 lies flat against the part 14 at the outer side of the hinge connection 17 when the wall sections 9 and 10 are brought to the perpendicular position shown in Figures 4 and 5. This folding of the corner portions 11 during the erection of the end walls of the box causes the side wall sections 7 at each side of the box to be swung upwardly and outwardly along the crease lines 24 joining the side walls sections 7 to the bottom wall section 6. When the box is in its fully set up condition, the parts 12 and 14 of each corner section 11 are folded flatly together and lie between the outer end wall sections 9 and the inner end wall sections 10. Obviously the relative movement which takes place between the parts 12 and 14 of the corner portions 11 during the erection of the side and end walls of the box to the fully set-up condition shown in Fig. 5 would not be possible if the end portions 20 of the inner end wall sections 10 were incapable of movement relative to the central portion 19. It is for this reason that the end wall sections 10 are provided with diagonal crease lines 18 to provide the movable end portions 20 which are movable in relation to the central portion 19 so as to take care of the necessary relative movement between the parts 12 and 14 of the corner sections 11 during the setting up of the box.

In the final set-up condition of the box, the flaps 21 joined to the portions 19 and 20 of the end wall sections 10 are disposed in an inwardly extending horizontal position resting flatly on the bottom wall 6 as shown in Fig. 5 with the outer ends of the flaps of the portions 20 abutting against the side walls 7 of the inner ends of said flaps butted against the ends of the flap 21 of the portion 19. In the present instance, the ends of the flap 21 of the central portion 19 of each end wall 10 and the butting ends of the flaps 21 of the portions 19 are shown mitred or cut at an angle but it will be understood that these abutting ends of the several flaps may be straight. The flaps 21 of the portions 19 and 20 of the end wall sections 10 serve, when arranged as shown in Fig. 5, to lock the free portions 20 of the end walls 10 against casual displacement. These flaps 21 also serve to strengthen and reinforce the end portion of the box.

In the slight modification shown in Fig. 6, the diagonal crease lines 18 of each end wall section 10 meet at their convergent ends and only the end portions 20 of these wall sections are provided with the locking flaps 21. In this case the inner ends of the flaps 21 of the portions 20 are butted together as shown in Fig. 6 with the outer ends of the flaps butted against the inner surfaces of the side walls 7.

The modification shown in Fig. 7 is the same as that shown in Fig. 6 except that the sides of the box are made of two-ply thickness and include inner side walls 7a hingedly joined at their upper edges to the side walls 7 which, in this case, constitute the outer side wall sections of the box.

Having thus described the nature and several preferred embodiments of my invention, it will be understood that the present disclosure is intended to be illustrative rather than limiting and that various modifications may be resorted

to within the scope and spirit of the invention defined by the appended claims.

I claim:

1. A box blank of the character described comprising a sheet of flexible material creased to define a bottom wall section, a side wall section hinged to each of the side edges of said bottom wall section, an outer end wall section hinged to each of the end edges of said bottom wall section, an inner end wall section of substantially the same dimensions as an outer end wall section hinged to each of said outer end wall sections, a plurality of relatively movable locking flap sections with their adjacent ends in abutting relation with respect to each other hinged to each of said inner end wall sections along an edge thereof which is parallel to the adjacent end edge of said bottom wall section, each inner end wall section being provided with a pair of diagonal crease lines extending thereacross and converging towards the edge of the inner end wall section to which the locking flap sections are attached and each of said crease lines intersecting a line of juncture between abutting ends of adjacent locking flap sections at said edge of the inner end wall section, and foldable corner sections joining the ends of each outer end wall section to the adjacent ends of the side wall sections.
2. A box comprising a bottom wall section, side wall sections having their lower edges joined to the side edges of said bottom wall section, outer end wall sections having their lower edges joined to the end edges of the bottom wall section, inner end wall sections of substantially the same height as said outer end wall sections having their upper edges joined to the upper edges of said outer end wall sections, a plurality of relatively movable locking flap sections with their adjacent ends in abutting relation with respect to each other joined to the lower edge of each inner end wall section and disposed in a horizontal position on the bottom wall section, each inner end wall section being provided with a pair of diagonal crease lines converging towards the lower edge of said section and each of said crease lines intersecting a line of juncture between abutting ends of adjacent locking flap sections at the lower edge of the inner end wall section, and foldable corner sections integrally connecting said side wall sections to said outer end wall sections at each corner of the box, each of said corner sections comprising two hingedly connected parts folded together in superimposed relation and disposed in place between the outer and inner end wall sections of the box.
3. A substantially flat, collapsed box of the character described comprising a sheet of flexible material creased to define a bottom wall section, a side wall section hinged to each of the side edges of said bottom wall section, an outer end wall section hinged to each of the end edges of said bottom wall section, an inner end wall section of substantially the same dimensions as an outer end wall section hinged to each of said outer end wall sections, a plurality of relatively movable locking flap sections with their adjacent ends in abutting relation with respect to each other hinged to each of said inner end wall sections along an edge thereof which is parallel to the adjacent end edge of said bottom wall section, each inner end wall section being provided with a pair of diagonal crease lines extending thereacross and converging towards the edge of the inner end wall section to which the locking

flap sections are attached and each of said crease lines intersecting a line of juncture between abutting ends of adjacent locking flap sections at said edge of the inner end wall section, and foldable corner sections joining the ends of each outer end wall section to the adjacent ends of the side wall sections, each of said corner sections comprising a first part hinged to an end of an outer end wall section and a second part hinged to said first part and to an end of a side wall section, said first part being attached to the outer end wall section at a point remote from the end thereof and attached to that portion of the ad-

jacent inner end wall section which lies between said crease lines.

DAVID H. SHAPIRO.
